ADJUSTABLE TYPEWRITER PLATFORM

Bruce E. Herbolzheimer, Auburn, Ind., assignor to Garrett Tubular Products, Inc., Garrett, Ind.

Filed Jan. 11, 1960, Ser. No. 1,504

7 Claims. (Cl. 248—23)

The present invention relates to an adjustable typewriter platform and more particularly to a unique and novel platform design which provides more space for a typist's knees and legs.

It is well known that typewriters should be situated at an optimum elevation, and to this end typewriter platforms incorporating means for varying the elevation have heretofore been provided. Such adjustable or variable elevation platforms comprise a basic frame structure which serves as a base on which the platform proper is adjustably mounted. This frame includes either a front cross-member or a flat plate which is fixed relative to the floor surface, thereby limiting the knee and leg room of a typist to the space beneath the cross-member.

These prior art constructions required such a base frame in order to accommodate manipulable mechanism by which the adjustable platform could be varied in elevation. For a short typist not needing particularly high platform elevations, this construction serves its purpose satisfactorily; however, for a tall person who needs to have the typewriter considerably elevated, he normally also requires a great deal more leg or knee room than is permitted by the fixed-height base frame. This being true, the mechanism fails to perform its intended purpose of accommodating satisfactorily and comfortably typists of radically different heights.

It is therefore an object of this invention to provide an adjustable typewriter platform wherein the adjustment of the platform proper serves in addition to provide an adjustment of the height of the space normally occupied by the typist's knees.

It is another object of this invention to provide an adjustable typewriter platform wherein the mechanism for adjusting the height is located outside the space normally occupied by a typist's knees.

Other objects will become apparent as the description proceeds.

To the accomplishment of the above and related objects, the invention may be embodied in the forms illustrated in the accompanying drawings, attention being called to the fact, however, that the drawings are illustrative only, and that specific change may be made in the specific constructions illustrated and described, so long as the scope of the appended claims is not violated.

In the drawings:

FIG. 1 is a front elevation of one embodiment of this invention shown as being mounted on a typical desk, a portion of the desk being broken away for clarity of illustration;

FIG. 2 is a sectional illustration taken substantially along the section line 2—2 of FIG. 1;

FIG. 3 is a bottom plan view of the typewriter platform of FIG. 1 also partially broken away for clarity of illustration;

FIG. 4 is a fragmentary bottom plan view of the same typewriter platform with the operating mechanism moved to a different position than shown in FIG. 3; and

FIG. 5 is a fragmentary illustration in perspective of one of the elevating-screw assemblies used in the construction of the preceding figures.

Referring to the drawings, and more particularly to FIGS. 2, 3 and 4, the mechanism includes a U-shaped base plate 10 which is preferably fabricated from light gauge sheet steel. The base plate 10 is substantially flat

2

with the exception that its edges are bent downwardly to provide a reinforcing perimetral flange 12. The two sides 14 and 16 of the base plate are elongated and parallel as shown, the rear ends 18 and 20 of the respective sides being integrally connected together by the base plate cross-member 22.

Secured to the top side of the base plate 10 are four upstanding supporting posts 24, 26, 28 and 30. These posts are substantially identically formed such that the description of one will suffice for all. Each post is preferably fabricated of sheet steel formed to a box-like shape but with the longitudinal edges of the section of sheet metal from which the post is fabricated spaced from each other to provide a longitudinally extending vertical slot 32. The bottom and top of each post are provided with two laterally extending flanges 34 and 36, respectively, the two flanges 34 being secured to the base plate 10 by means of rivets or the like. These four posts may be considered in pairs, the two posts 24 and 26 being characterized as the front posts since they are located near the front ends of the two base plate sides 14 and 16, respectively. Similarly, the posts 28 and 30 may be characterized as the rear posts since they are located toward the rear ends of these sides, respectively. The slots 32 in the various posts are arranged such that the slots in the front posts 24 and 26 face each other and are parallel, as are the slots in the two rear posts 28 and 30 with respect to each other.

Two rigid strap steel braces 38 and 40 are connected to the tops of the respective front and rear posts 24, 28 and 26, 30. The braces are attached rigidly to the respective post tops by means of rivets passing through the flanges 36 as shown more clearly in FIG. 5. As seen more clearly in FIG. 3, the four posts are located with respect to each other at the four corners of an imaginary rectangle.

Mounted inside the posts 24, 26, 28 and 30 are four substantially identical upstanding screws 42, 44, 46 and 48, respectively, each in registering alignment with the respective slot 32. Each screw is journaled at its opposite ends in the base plate 10 and one of the two braces 38, 40, respectively. For example, the bottom end of the screw 42 is journaled in a bearing aperture in the base plate 10 while the upper end is journaled in a bearing aperture in the brace 38.

Fixedly secured to the bottom end of each screw and disposed adjacent the underside of the base plate is a flat steel operating arm 50, the arm extending radially or laterally from the screw. A U-shaped pitman or connecting rod, indicated generally by the reference numeral 52, is also located adjacent to the underside of the base plate 10 and is constructed to conform to both the size and shape of the base plate (FIG. 3). This pitman 52 must be rigidly constructed so for this reason is provided with two spaced-apart angle irons 54 and 56 as cross-members which are secured to the rear ends of the two flat steel side bars 58 and 60, respectively. Additional reinforcement between the cross members 54 and 56 and the side bars 58 and 60 is provided by the two corner braces 62 welded preferably in the positions as shown in FIGS. 3 and 4.

The pitman 52 is pivotally connected to each of the operating arms 50 as shown by means of a respective pivot pin 64, this pivot pin being spaced from the axis of the respective screw. All of the operating arms 50 and lever lengths thereof are of substantially the same length, so that the pitman 52 may be rotated in a plane parallel to the base plate to rotate all of the screws in unison. Operation of the pitman 52 is accomplished by means of a crank 66 composed of a first link 68 pivoted at one end by means of a pin 70 to the base plate and fixedly secured at the other end to a pin 72 which projects

through the side arm 60 of the pitman. The lower end of the pin 72 as viewed in FIG. 2 is fastened securely to the handle portion 69 of the crank 66 as shown. The opening in the pitman arm 60 which accommodates the pin 72 is large enough to provide for a rotational connection therewith. By disposing the pivot pin 70 on a straight line which intersects the axes of the front and rear screws 42 and 46, and by further locating the pin 72 from the pin 70 a distance equal to the operating lengths of the individual arms 50, the crank 66 may be rotated to in turn impart a rotational motion to the pitman 52 for rotating all of the screws in unison.

Two elongated supporting bars 74 and 76, preferably formed of channel-shaped steel, are threadedly mounted at the opposite ends thereof to the front and rear screws respectively. Each bar is provided at its opposite ends with a T-shaped nut member 78, the stem of the T being rigidly secured to the respective bar as indicated more clearly in FIGS. 3 and 5. Preferably, the sides of the bar are tightly wrapped around the stem to provide the secure connection. By means of this connection, the nut member becomes an integrated part of the respective bar.

The outer extremity of each nut member 78 has a threaded aperture which is threadedly mounted on the respective screw as more clearly shown in FIG. 5, the stem of the nut member passing through the slot 32 in the respective post. By means of this threaded connection, rotation of the screw will cause the nut member as well as the respective bar to be moved upwardly or downwardly, depending upon the direction of screw rotation.

The bar 74 is threadedly connected at its opposite ends to the front screws 42 and 44, while the rear bar 76 is similarly connected to the rear screws 46 and 48. By locating these bars 74 and 76 equal distances above the base plate 10 to start with, rotation of the four screws in unison will serve to raise or lower the bars in unison, depending upon the direction of screw rotation.

FIG. 1 illustrates the mechanism thus far described as being fastened to an ordinary desk having a typewriter well or recess 80. The illustrated method of securing the mechanism to the desk is shown more clearly in FIG. 2, suitable bolts or screws 82 being used to clamp the braces 38 and 40 to the underside of the desk top on opposite sides, respectively, of the typewriter well. As shown in FIG. 2, three such screws are used for this purpose. By this means of fastening, the mechanism is in effect suspended from the underside of the desk top in registration with the typewriter well 80.

In operation, the two bars 74 and 76 constitute a platform on which a typewriter may be placed. By rotating the crank 66, all of the screws will be rotated in unison, thereby moving the platform bar 74 and 76 upwardly or downwardly as the case may be.

An important feature of this invention resides in the fact that the front portion of the mechanism is completely open, this being accomplished by providing the base plate 10 and the pitman 52 with a U-shape. Since the typist's knees are located underneath the base plate, it becomes obvious that nothing in the forward or front portion of the base plate can interfere with or contact the typist's knees. The lowest structure adjacent the front end of the mechanism is the platform bar 74; however, for a tall person requiring more knee room, this is automatically provided when the person adjusts the typewriter stand to the necessary height for comfortable typing. Thus, by means of a single adjustment, more knee room is provided for the taller person when the typewriter height is adjusted to the proper level.

While a pitman 52 has been illustrated and described in connection with providing simultaneous rotation of the four screws, a chain and sprocket connection may be used instead to provide the same operation. In this arrangement, a small sprocket is attached to the bottom

end of each screw adjacent to the underside of the base plate and a chain is passed around the sprockets along a U-shaped path in parallelism with the shape of the base plate. A crank attached to one sprocket is used to impart rotation to the latter, whereby all of the sprockets and screws are rotated in unison. Use of the pitman 52, however, is preferred as it is more economical and foolproof than the chain and sprocket drive.

What is claimed is:

- 10 1. An adjustable typewriter platform comprising a U-shaped base plate having two substantially parallel elongated sides, four upstanding supporting posts spaced apart and secured to the top side of said base plate at the front and rear ends of said sides respectively, said posts
15 being hollow and slotted longitudinally, two elongated braces extending parallel to said sides respectively, said braces being secured at the opposite ends thereof to the tops of the respective front and rear posts, four upstanding screws disposed inside said four posts respectively,
20 one end of each screw being journalled in said base plate and the other end of each screw being journalled in the respective brace, two horizontally disposed supporting bars extending transversely of said base plate sides and spanning the space therebetween, the opposite ends of
25 said bars having nut members thereon, the nut members of one bar being threadedly received by the two screws respectively in the front posts, the nut members of the other bar being threadedly received by the two screws respectively in the rear posts, said bars extending through
30 the slots of the respective posts, four operating arms, one arm each being fixedly secured at one end to the lower end of each screw to extend laterally of the latter, a U-shaped pitman of substantially the same size and shape as said base plate, said pitman being disposed adjacent
35 to and in parallelism with the underside of said base plate, the other ends of all said operating arms pivotally connected to said pitman, and a crank arm comprising a link disposed between said base plate and said pitman and pivotally connected at one end to said base plate,
40 and a handle portion disposed on the other side of said pitman from said link and fastened at one end to the other end of said link by a pin which extends through an opening in said pitman, said opening in said pitman accommodating rotation of said pin whereby rotation
45 of said crank arm serves to rotate all of said screws in unison.

2. An adjustable typewriter platform comprising a U-shaped base plate having two substantially parallel elongated sides, four upstanding supporting posts spaced apart and secured to the top side of said base plate at the front and rear ends of said sides respectively, said posts being hollow and slotted longitudinally, four upstanding screws disposed inside said four posts respectively, one end of each screw being journaled in said base plate and the other end of each screw being journaled in the upper end of the respective post, two horizontally disposed supporting bars extending transversely of said base plate sides and spanning the space therebetween, the opposite ends of said bars having nut members thereon, the nut members of one bar being threadedly received by the two screws respectively in the front posts, the nut members of the other bar being threadingly received by the two screws respectively in the rear posts, said bars extending through the slots of the respective posts, four operating arms, one arm each being fixedly secured at one end to the lower end of each screw to extend laterally of the latter, a U-shaped pitman of substantially the same size and shape as said base plate, said pitman being disposed adjacent to and in parallelism with the underside of said base plate, the other ends of all said operating arms being pivotally connected to said pitman, and a crank arm comprising a link disposed between said base plate and said pitman and pivotally connected at one end to said base plate, and a handle portion disposed on the other side of said pitman from said link and fastened

at one end to the other end of said link by a pin which extends through an opening in said pitman, said opening in said pitman accommodating rotation of said pin whereby rotation of said crank arm serves to rotate all of said screws in unison.

3. An adjustable typewriter platform comprising a U-shaped base plate having two substantially parallel elongated sides, four upstanding supporting posts spaced apart and secured to the top side of said base plate at the front and rear ends of said sides respectively, said posts being hollow and slotted longitudinally, four upstanding screws disposed inside said four posts respectively, one end of each screw being journaled in said base plate and the other end of each screw being journaled in the upper end of the respective post, two horizontally disposed supporting bars extending transversely of said base plate sides and spanning the space therebetween, the opposite ends of one bar being threadedly mounted on the two front screws and the opposite ends of the other bar being threadedly mounted on the rear screws, four operating arms, one arm each being fixedly secured at one end to the lower end of each screw to extend laterally of the latter, a U-shaped pitman of substantially the same size and shape as said base plate, said pitman being disposed adjacent to and in parallelism with the underside of said base plate, the other ends of all said operating arms being pivotally connected to said pitman, and a crank arm comprising a link disposed between said base plate and said pitman and pivotally connected at one end to said base plate, and a handle portion disposed on the other side of said pitman from said link and fastened at one end to the other end of said link by a pin which extends through an opening in said pitman, said opening in said pitman accommodating rotation of said pin whereby rotation of said crank arm serves to rotate all of said screws in unison.

4. An adjustable typewriter platform comprising a U-shaped base plate having two substantially parallel elongated sides, four upstanding supporting posts spaced apart and secured to the top side of said base plate at the front and rear ends of said sides respectively, said posts being hollow and slotted longitudinally, four upstanding screws disposed inside said four posts respectively, one end of each screw being journaled in said base plate and the other end of each screw being journaled in the upper end of the respective post, two horizontally disposed supporting bars extending transversely of said base plate sides and spanning the space therebetween, the opposite ends of one bar being threadedly mounted on the two front screws and the opposite ends of the other bar being threadedly mounted on the rear screws, and means for rotating all of said screws in unison.

5. An adjustable typewriter platform comprising a U-shaped base plate having two substantially parallel elongated sides, four upstanding screws spaced apart and journaled at one end in said base plate at the front and rear ends respectively of said sides, said screws being located at the corners of an imaginary rectangle, means on said base plate for supporting said screws in upstanding position, two horizontally disposed supporting bars extending transversely of said sides and spanning the space therebetween, opposite end portions of one bar being threadedly mounted on the two front screws respec-

tively and opposite end portions of the other bar being threadedly mounted on the two rear screws respectively, four operating arms, one arm each being fixedly secured at one end to the lower end of each screw to extend laterally of the latter, a U-shaped pitman of substantially the same size and shape as said base plate, said pitman being disposed adjacent to the underside of and arranged in parallelism with said base plate, the other ends of all said operating arms being pivotally connected to said pitman, and a crank arm comprising a link disposed between said base plate and said pitman and pivotally connected at one end to said base plate, and a handle portion disposed on the other side of said pitman from said link and fastened at one end to the other end of said link by a pin which extends through an opening in said pitman, said opening in said pitman accommodating rotation of said pin whereby rotation of said crank arm serves to rotate all of said screws in unison.

20 6. An adjustable typewriter platform comprising a U-shaped base plate having two substantially parallel elongated sides, four upstanding screws spaced apart and journaled at one end in said base plate at the front and rear ends respectively of said sides, said screws being located at the corners of an imaginary rectangle, means on said base plate for supporting said screws in upstanding position, platform means threadedly mounted on said front and rear screws, four operating arms, one arm each being fixedly secured at one end to the lower end of each screw to extend laterally of the latter, a U-shaped pitman of substantially the same size and shape as said base plate, said pitman being disposed adjacent to the underside of and arranged in parallelism with said base plate, the other ends of all said operating arms being pivotally connected to said pitman, and a crank arm having a portion pivotally connected at one end to said base plate and at its other end to said pitman whereby rotation of said crank arm serves to rotate all of said screws in unison.

40 7. An adjustable typewriter platform comprising a U-shaped base plate having two substantially parallel elongated sides, four upstanding screws spaced apart and journaled at the one end in said base plate at the front and rear ends respectively of said sides, said screws being located at the corners of an imaginary rectangle, means on said base plate for supporting said screws in upstanding position, platform means threadedly mounted on said front and rear screws, four operating arms, one arm each being fixedly secured at one end to the lower end of each screw to extend laterally of the latter, a U-shaped pitman of substantially the same size and shape as said base plate, said pitman being disposed adjacent to the underside of and arranged in parallelism with said base plate, the other ends of all said operating arms being pivotally connected to said pitman, and means connected to said U-shaped pitman for imparting rotary motion thereto and in turn to said four upstanding screws.
